UNITED STATES PATENT OFFICE.

PAUL DUPONT, OF PARIS, FRANCE.

ENAMELING AND ANNEALING FURNACE.

1,335,279.

Specification of Letters Patent. Patented Mar. 30, 1920.

Application filed March 14, 1918. Serial No. 222,449.

To all whom it may concern:

Be it known that I, PAUL DUPONT, a citizen of the Republic of France, residing at Paris, France, have invented new and useful 5 Improvements in Enameling and Annealing Furnaces; and I do hereby declare that the following is a full, clear, and exact description of the invention, which will enable others skilled in the art to which it appertains to make and use the same.

My invention relates to improvements in enameling and annealing furnaces and is shown in the annexed drawings as applied to the enameling of a bath, but it is obvious that it may be made of any suitable 15 shape corresponding to that of the object or article to be enameled.

Figure 1 is a transverse section of my improved furnace and

20 Fig. 2 is a part of a transverse section relating to a modification of the furnace shown in Fig. 1.

The furnace consists of an outer wall or sheath C and an inner wall A of highly 25 porous refractory material of suitable thickness, and having preferably the shape of a bath such as B and of suitable size to allow for a proper space α being formed between the wall and the bath B; after the latter 30 has been introduced into the furnace.

This refractory inner wall is covered outside with a metal sheath C having extensions c with slightly turned up edges serving to support the edge b of the bath.

35 By suitable means such, for example, as the collars d formed in the wall A, a very small space e is maintained between the wall and its sheath, so as to allow a free circulation of the gaseous mixture for heating the 40 furnace, as hereinafter more fully explained.

At different parts of the sheath, provided with corresponding apertures, are attached short tubes D for the introduction of a mixture of combustible gas and air or oxygen 45 under pressure. The combustible gas, the proportions of the mixture and its pressure may be varied according to the temperature which it is desired to obtain. The combustible gas can, for example, be the town lighting gas, acetylene, hydrogen, or any other suitable gas. Wire gauze partitions f are arranged perpendicularly in the inlet pipes 50 D for the mixture so as to prevent the ignition of the gas in the said pipes.

55 On the sheath are also arranged small ignition burners E, extending to the inner

face of the wall A and connected independently of the combustible mixture directly to the source of combustible gas, as well as a discharge passage F for the burnt gases 60 communicating with the interior of the furnace by means of openings G in the wall A.

The arrangement just described constitutes the furnace proper. It can advantageously 65 be mounted upon a double support in such a manner as to be suitably inclined longitudinally and transversely for purpose of facilitating the powdering of inner face of the bath B which is introduced therein. 70

This furnace is completed by a flat cover of analogous construction, that is to say, provided with a lining A of very porous refractory material contained in a metal sheath C with a small intermediate space e 75 and short tubes D for the introduction of combustible mixture, ignition burners E and openings and discharge passage G, F. The wall A of very porous refractory material is, however, replaced at the angles by angle 80 pieces K of non porous refractory material for protecting the edge b of the bath from too fierce a fire. Moreover, a mica-covered peep-hole, (not shown) is provided at a suitable point of the surface of the cover 85 for ascertaining the degree of heat in the bath under treatment.

For cast iron articles an auxiliary stove heated by the burnt gases issuing from the furnace through the passages F before their 90 escape into the air may be used as usual, in order to raise the bath to a given temperature before it is placed in the furnace.

The different passages opening into the apparatus are provided with regulating devices such as dampers, valves, etc., and a flexible portion for allowing the displacement of the furnace proper and of its cover. 95

The discharge passages F for the burnt gases may be preferably, provided for a certain portion of their length with a double casing through which an air is blown under pressure in order to be heated before being mixed with the combustible gas, so as to increase the temperature of combustion of 100 the mixture in the furnace.

The furnace is employed in the following manner:

After having previously heated the bath in the auxiliary stove aforesaid, it is placed 110 in the furnace proper, on which the cover is then placed as shown in Fig. 1, then the

combustible mixture is admitted which, by reason of the resistance offered to its passage by the refractory material A, becomes distributed first, in the space *e* and afterward throughout the mass of the said porous refractory material. Immediately after it has passed through the latter it is ignited by the burners E, which are always alight, in order to avoid any risk of explosion.

10 The wall A is thus rapidly brought to incandescence, its thickness being calculated according to the nature of the gas employed, so as to obtain this result.

When it has been found by the peep-hole 15 in the cover, that the bath has reached the proper degree of temperature, the cover is lifted by means of a windlass and chains for example. But the furnace proper, always heated, is sufficient for continuing to raise 20 the temperature of the bath B while the operator is proceeding to the powdering which can thus be effected in a single operation.

In some cases the thickness of the refractory material of the wall A can be lessened so as to leave between it and the outer metal sheath C a larger space *e* Fig. 2 into which can open a series of burners L uniformly distributed over the whole surface 30 of the sheath in order to bring the said refractory material to incandescence. In this case the refractory material used can be porous or not and reinforced by a metal plate M which will increase its resistance. 35 Ignition burners E similar to those before mentioned would serve always for lighting the burners which would be then sufficiently near together to prevent explosions.

It is obvious that the described furnace 40 for enameling baths is applicable, with suitable modifications of the shape, for enameling and, in a more general manner, for the heating of any metal articles.

I claim as my invention:

45 1. In a furnace, the combination of a bath, a source of combustible material, means between the bath and the source of combustible

material to effect a distribution of the un-ignited combustible material around the bath and means between the first-named means 50 and the bath to ignite the distributed material.

2. In a furnace, the combination of a bath, a source of combustible material, a permeable layer between the bath and the source 55 of combustible material to effect a distribution around the bath, and means to ignite the distributed material between the layer and bath.

3. In furnaces for enameling and annealing, the combination of a chamber of a shape suitable for the objects to be treated therein, consisting of an inner wall of porous refractory material, an outer wall or sheath and an intermediate space between the two 65 for the free passage of gas, said sheath being provided with short tubes for the mixture of combustible gas and air under pressure, while ignition burners protrude through said inner wall, and a conduit for 70 burnt gases communicates with the inside of the furnace by suitable openings, said furnace being surmounted by a lid or cover of similar construction to that of the chamber provided with angle pieces of non porous 75 material.

4. In furnaces for enameling and annealing, the combination of a chamber of a shape suitable for the objects to be treated therein, consisting of an inner wall of porous refractory material, an outer wall or sheath and a small intermediate space between the two maintained by a number of collars, said sheath having extensions with turned up 80 edges and short tubes provided with wire 85 gauzed partitions to prevent ignition as and for the purpose set forth.

In witness whereof, I have hereunto signed my name in the presence of two subscribing witnesses.

PAUL DUPONT.
